UNITED STATES PATENT OFFICE

2,440,870

COMBING MACHINE FOR TEXTILE FIBRES

John William Nasmith, Heaton Mersey,
Manchester, England

Application September 19, 1941, Serial No. 411,835
In Great Britain November 15, 1940

Section 3, Public Law 690, August 8, 1946
Patent expires November 15, 1960

3 Claims. (Cl. 19—121)

1

In the specification of United States Letters Patent No. 2,145,491 granted to me there is described and claimed a form of combing machine for textile fibres. The apparatus operates fundamentally in the manner well known in combing machines of the rectilinear type; that is to say that a tuft of fibres is combed by drawing it through a top comb and such tuft, being combed, is detached and pieced up to the end of an already combed fleece of fibres, which end is returned or backed off for the purpose. The combed tuft, now constituting the end of the continuous fleece, is backed off on the next combing for the piecing up of a further combed tuft, and so on. In the specification referred to, however, the lower piecing roller of a pair of piecing rollers is reciprocated bodily to and from the usual combing cylinder position for the purposes set forth in the specification, and there are provided forms of control for a returned or backed off end. In one form, this control is constituted by a pair of aprons having contiguous plane faces, which faces reciprocate in synchronism with the circumferential speed and direction of rotation of the lower piecing roller as the latter rotates to deliver and then take up the returned or backed off end of fleece in the piecing operation. See Figures 6 and 7 of the drawings of the specification, and the relevant description.

Both aprons are, in the apparatus being referred to, quite separate from the pair of piecing rollers, except as to their cooperative function therewith, and as a result there is a considerable free space between the nip of the rollers and the nip of the aprons at the point where a returned end enters between the faces of the latter. Whilst the apparatus works well, and is found, due to the form of control of the returned end of fleece, very suitable for long fibres such as wool, the necessity of presenting the free returned end of fleece to this free space, and causing it to cross the same before it reaches the control aprons, is liable to result in some straggling of the end fibres of the fleece. This is particularly noticeable where the combing of wool fibres is in question, as, due to friction set up as the fibres are pulled through the top comb together, a static electric charge is generated in each individual fibre, and these as a result feebly but definitely repel each other, with disturbance of the smooth parallelism of the said fibres as components of the fleece. The static charge of each fibre is at this point at its maximum in the free space, where in addition they are unsupported.

One object of the present invention is to pro-

2

vide a form of apron control wherein the extent of the free space above mentioned will be reduced to the minimum, thus ensuring an earlier grip by the aprons upon the end fibres and eliminating their straggling due to the static electric charge as pointed out, or to any other cause. To this end the present invention is characterised in that the apron pair is constituted by an upper apron and a lower apron, of which one, the upper apron, passes around the lower piecing roller and takes part bodily in the sliding movement to and from the combing cylinder position, and that the operative upper face of the lower apron is extended and contracted as to effective length in relation to the contiguous face of the upper apron whilst preserving uniformity of co-operative movement of the contiguous apron faces. As a result of this combination there is, at the appropriate time, a space left upon the end of the face of the lower apron below the nip point of the piecing rollers to receive directly the returned end of fibre fleece, this end being then taken immediately into the nip of the apron faces from the nip of the piecing rollers.

Another object of the present invention is to provide means for ensuring that the static electric charges of the fibres shall be dissipated before the continuous length of combed fleece is released to be formed as usual into a sliver. This is effected by forming the upper face of the upper apron of sufficient length to allow of the returned end of fleece lying thereupon with a series of pieced up fibre tufts constituting successively formed ends of the same, so that the static electric charges are entirely dissipated from the fibres before the fleece leaves the face of the apron as a result of the successive reciprocations of the latter.

The invention, with a convenient and practical arrangement and method of operation of the aprons, will now be described for a full understanding of the same, reference being had to the annexed drawings. In these drawings, Figure 1 is a cross section through the piecing and other rollers and through the pair of aprons at the end of the tuft detaching period; and Figure 2 is a similar view of the parts in their position when the return of the end of fleece is about to begin.

Referring first to Figure 1, the roller 1 is mounted in fixed but adjustable bearings of known character and the endless apron L, which is of soft leather, passes around such roller and is carried in a direction as horizontal as possible around the roller 2 and the tension or compensating roller 3. Roller 2 is coarsely fluted as shown.

Around the lower piecing roller P passes a further endless apron of soft leather L' supported by the roller 4, also coarsely fluted. The roller 2 is in bearings which are adjustable so that its flutes can be caused to engage slightly with the flutes of roller 4 through the aprons L and L' to grip the said aprons between them so that the faces of the latter will move together in their reciprocation. The roller 4, which is the driving roller, is given rotary movement first in one direction and then the reverse, to give this desired reciprocatory movement. The lower piecing roller P is mounted in bearings to which is imparted a sliding motion—see Figure 1 of the drawings of specification 2,145,491—and the bearings of the roller 4 are also conveniently mounted in the same slide mechanism. Sliding movement from the position of the apparatus shown in Figure 1 to that of Figure 2 is thus imparted to the bearings of roller P, as also in this case to the bearings of roller 4, and the bearings of roller 2, also slidably mounted, participate in this movement. The tension roller 3 is carried in bearings mounted on lever 6 which is constantly under the influence of the downward pull of a tension spring at 5 attached thereto, so that the apron L is kept constantly taut. A delivery roller 8 may be used to direct the fleece x as it leaves the apron L' at T', to be condensed into a sliver in known manner. S indicates the combing cylinder; 35 the cylinder cover as in specification No. 2,145,491 and D the detaching roller. A supporting tension roller for the upper length of apron L' is indicated at 7.

In Figure 1 the apparatus is shown at the end of the fibre tuft detaching period, and the tail of this tuft is taken into the nip of the rollers P and P', projecting therefrom as shown at T to a length about equal to half the diameter of the roller. This is a very short free end, and the fibres are stiff enough to resist the effect of the static electric charge upon the fibres.

In Figure 2 the apparatus is shown in the position when the rollers are about to reverse to deliver the end of the fleece for piecing. The driving roller 4 and the roller P, the former entraining the roller 2, have moved away from the cylinder S and its cover 35, and the falling upper piecing roller P' has dropped behind the roller P in the manner described in the specification No. 2,145,491, so that in this construction it nearly touches the lower endless apron L. The piecing rollers and the faces of the aprons then begin to move in the direction of the arrows Figure 2, and it will be seen that the distance from the nip of the rollers P and P' to the apron L is very short, so that the tips of the fibres T are immediately carried forward between the aprons L and L' without being obliged to traverse any space of an extent sufficient to allow them to disperse, due to their electric charges, as a

result of undesired lengthening of the free fibre and of the fleece between the nip of the rollers P and P', and their engagement by the aprons.

The apparatus then returns to the position of Figure 1, ready for the next detaching and piecing operation. The fleece, on issuing from the nip of the roller P' and the contiguous faces of the aprons L and L', is supported upon the upper face of the upper apron L', and adheres thereto during several successive detachings and piecings, until it reaches the discharge point at roller 8. Thus, between the piecing rollers and the roller 8 there are at all times a succession of superposed detached fibre tufts, each constituting in its turn the end of the fleece, and the static electric charges on the fibres have time to dissipate before the said fleece leaves the apron to be formed and compressed into a sliver.

I claim:

20 1. In a combing machine for textile fibres, upper and lower piecing rollers reciprocating around their respective axes and the lower roller being also bodily reciprocatable, an endless upper apron passing around the lower piecing roller and thus having lineal and bodily movement imparted thereto, a further apron having a face forming an apron nip with a face of the upper apron, and means for extending and contracting the effective length of such lower apron face in 30 synchronism with the movements of the contiguous face of the upper apron.

2. In a combing machine for textile fibres, upper and lower piecing rollers reciprocating around their respective axes and the lower roller being also bodily reciprocatable, a rotatable and bodily movable carrier roller, an endless apron supported by such roller and by the lower piecing roller, a further endless apron having a face which forms a nip with a face upon the first 35 apron to follow lineally and bodily the lineal and bodily movements of the said first apron, and a compensation tensioning roller within the further endless apron.

3. In a combing machine as claimed in claim 1, an endless upper apron having an upper surface of sufficient length to accommodate a length of fibre fleece consisting of successively pieced up combed fibre tufts, for the purpose hereinbefore set forth.

JOHN WILLIAM NASMITH.
